UNITED STATES PATENT OFFICE.

EDWIN RUUD, OF PITTSBURG, PENNSYLVANIA.

WATER-VALVE FOR INSTANTANEOUS WATER-HEATERS.

No. 879,910.

Specification of Letters Patent.

Patented Feb. 25, 1908.

Application filed April 8, 1907. Serial No. 367,081.

To all whom it may concern:

Be it known that I, EDWARD RUUD, of Pittsburgh, in the county of Allegheny and State of Pennsylvania, have invented a certain new and useful Improvement in Water-Valves for Instantaneous Water-Heaters, of which improvement the following is a specification.

My present invention relates to piston actuated water valves for opening the gas valves of automatic instantaneous water heaters, and its object is to provide a simple and inexpensive construction, by the employment of which the objections heretofore obtaining in the operation of appliances of this type will be effectually overcome, these being more particularly, in the binding and failure of action of the piston due to the springing of the piping, and the comparatively large area subject to leakage, and lack of dash pot control, which causes the abnormal movement of the piston by reaction or "water hammering," thereby turning on the gas when no water is drawn from the cold water faucet, instead of operating to open the gas valve when, and only when, its opening is required.

The improvement claimed is hereinafter fully set forth.

In the accompanying drawings; Figure 1 is a longitudinal section through an appliance embodying my invention, on the line *aa* of Fig. 3; Fig. 2, a similar section, with the piston and valve shown in elevation, on the line *bb* of Fig. 3; and, Fig. 3, a transverse section, on the line *cc* of Fig. 1.

In the practice of my invention, I provide a casing or cylinder, 1, having one of its ends closed by a removable cap or cover, 2, and having formed upon its body an inlet nozzle, 3, to which is connected a water supply pipe, 4, and an outlet nozzle, 5, to which is connected a water delivery pipe, 6, leading to an automatic instantaneous water heater of construction such as is well known in the art. The inlet and outlet nozzles are separated by a valve seat partition or division wall, 7, extending across the cylinder, and having a central opening controlled by a valve, 8, which is in this instance shown as of cylindrical or piston form, and fitting, when closed, in the central opening of the partition, 7. The valve, 8, is connected by a cylindrical body, 9, with an operating piston, 10, which may be provided with a packing ring, 11, and which fits truly in the cylinder, 1, between the cap, 2, and a transverse partition, 12, ex-

tending across the cylinder, the space around the cylindrical body, 9, between the piston, 10, and partition, 12, serving as a dash pot chamber. The cylindrical body 9 also acts as a guide for the piston 10 and valve 8. Passages, 13, are formed in the body, 9, for the admission of water, at supply pressure, from the inlet nozzle to the cylinder, on the outer side of the piston, and a communication passage, 14, is formed in the tubular body, to admit a limited traverse of water from the inlet to the outlet nozzle. If preferred, the function of the passage, 14, may be performed by a corresponding groove or passage formed in the periphery of the valve, or the valve may be fitted sufficiently loosely in the central opening of the partition, 7, to permit a limited traverse of water around it when seated in said opening. A passage, 15, is also formed in the partition, 12, to permit the discharge of water from the dash pot chamber to the outlet nozzle, and a drain passage, 16, is formed near the bottom of said partition, communicating with a discharge opening which is closed by a screw, 17.

A plurality of recesses is formed in the periphery of the valve, 8, at the end thereof nearer the piston, the metal between said recesses forming guides, 8^a, by which the valve is maintained in true axial alinement with the piston when unseated, and prevented from being locked or binding against its seat. A valve stem, 18, abuts against a transverse head, 19, formed by a partition in the bore of the cylindrical body, 9, and extends outwardly through a stuffing box, 20, in the casing, in position to actuate the gas valve, when the valve, 8, is unseated, in the ordinary manner. The piston is returned to, and normally held in, position to seat the connected valve, by a spring, 21, abutting against the enlarged end of stem 18 and the closed end of the casing.

In operation, water, at supply pressure, passes from the inlet nozzle, 3, through the passages, 13, to the cylinder space on the back or left hand side of the piston, 10, and also passes through the communication passage, 14, to the outlet nozzle, 5, and, through the same and the connected piping of the water heater, to the spigot which controls the delivery of hot water. When the spigot is opened, the pressure on the delivery side of the valve, 8, and piston, 10, is thereby lowered, and the piston, 10, is forced forward, or to the right, by the then higher pressure

on its left hand side, carrying with it and unseating the connected valve, 8, and thereby permitting the delivery of water while the spigot remains open. The speed of movement of the piston is controlled by the size of the dash pot chamber discharge passage, 15, and the unseating of the valve opens the gas valve, through the valve stem, 18, in the usual manner, for the purpose of heating the water in its traverse through the heater coils. When the spigot is closed, the pressure on the delivery side of the valve begins to increase, and as it approaches that on the supply side of the valve, the spring, 21, returns the piston to normal position and seats the valve, the speed of the return movement of the piston and valve being controlled by the size of the passages, 14, and 15, which provide for the filling of the chamber caused by the displacement of the piston through its rearward traverse.

I claim as my invention and desire to secure by Letters Patent:

1. In a valve mechanism for instantaneous water heaters, the combination of a casing provided with water inlet and outlet connections, a valve controlling communication between said connections, a piston fitting a cylindrical chamber in the casing and connected integrally to the valve by a cylindrical body which forms a dash pot between said valve and heater, said casing also provided with passages establishing communication between the inlet connection and one side of the piston, between the opposite side of the piston and the outlet connection, and between the inlet and outlet connections past the valve, a gas valve actuating stem connected to the valve, and a spring bearing on the valve in direction to impart closing movement thereto.

2. In a valve mechanism for instantaneous water heaters, the combinations of a casing provided with water inlet and outlet connections, a piston and dash pot chamber in said casing separated by a partition from said inlet and outlet connections, a valve seat partition interposed between the inlet and outlet connection, a valve controlling an opening in the valve seat partition, a piston fitting in the piston and dash pot chamber and connected integrally to the valve by a cylindrical body, said casing also provided with passages through said cylindrical body establishing communication between said chamber and the inlet connection,

on one side of the piston, between said chamber and the outlet connection on the opposite side of the piston, and between the inlet and outlet connections past the valve, a gas valve actuating stem connected to the valve and a spring bearing on the valve in direction to impart closing movement thereto.

3. In a valve mechanism for instantaneous water heaters, the combination of a casing provided with water inlet and outlet connections, a piston and dash pot chamber in said casing separated by a partition from said inlet and outlet connections, a valve seat partition interposed between the inlet and outlet connections, a valve controlling an opening in the valve seat partition, a piston fitting in the piston and dash pot chamber, a cylindrical body passing through the partition of said chamber and connecting the piston and valve, said casing also provided with passages establishing communication between said chamber and the inlet passage, on the side of the piston further from the valve, between said chamber and the outlet connection, through the partition of the chamber, and between the inlet and outlet connections past the valve, a gas valve actuating stem connected to the valve, and a spring bearing on the valve in direction to impart closing movement thereto.

4. In a valve mechanism for instantaneous water heaters, a combined water valve and motor, comprising a valve, a piston, a dash pot between the valve and piston, a cylindrical body integrally connecting the valve and piston and forming a guide and provided with a passage for the traverse of water from one side of the piston to the other, a transverse head formed in said cylindrical body, and a spring actuated valve stem seated against said head.

5. In a valve mechanism for instantaneous water heaters, a combined water valve and motor, comprising a cylindrical valve having a plurality of peripheral guides, a piston, a tubular body connecting the valve and piston, passages in the body for the traverse of water from one side of the piston to the other and from one side of the valve to the other, and a transverse partition in the body interposed between said passages.

EDWIN RUUD.
